Primary Examiner — Mary Ann Calabrese*Assistant Examiner* — Hillary Catherine Shepard(74) *Attorney, Agent, or Firm* — Avek IP, LLC(57) **CLAIM**

The ornamental design for a seat, as shown and described.

DESCRIPTION

FIG. 1 is a perspective view for a seat showing our new design;

FIG. 2 is a front view of the seat of FIG. 1;

FIG. 3 is a back view of the seat of FIG. 1;

FIG. 4 is a left view of the seat of FIG. 1;

FIG. 5 is a right view of the seat of FIG. 1; and,

FIG. 6 is a top view of the seat of FIG. 1.

In FIGS. 1-6, broken lines indicate environmental structure that forms no part of the claimed design.
